STADIUM SEAT UNIT

Lloyd H. Cary, Magnolia, Ark., assignor to Southern Extrusions, Inc., Magnolia, Ark., a corporation of Arkansas

Filed Nov. 29, 1968, Ser. No. 14,714

Term of patent 14 years

Int. Cl. D6—01

U.S. Cl. D15—8

FIG. 1

FIG. 2

FIG. 3

FIG. 2 is a back view of FIG. 1;

FIG. 3 is a left hand end view of FIG. 1; and
FIG. 4 is a top plan view of FIG. 1.

I claim:

The ornamental design for a stadium seat unit, substantially as shown.
